UNITED STATES PATENT OFFICE

2,425,460

OVERALL TYPE GARMENT

Willa H. Davis, New York, N. Y., assignor to
Mills B. Lane, Jr., Atlanta, Ga.

Application September 7, 1946, Serial No. 695,425

2 Claims. (Cl. 2—227)

1

This invention pertains to apparel and more especially to a bifurcated outer garment of the overall type. While primarily intended as a child's garment, the broader aspects of the invention are capable of embodiment in garments for adult use.

One object of the invention is to provide an overall garment having a bib front and which is easy to don and remove. A further object is to provide a garment which opens at the front of the waistband and which has a fly front, but which is so devised that the fly front is normally concealed by the bib, although is readily accessible by dropping the bib. A further object is to provide a garment of this type having ample pocket space at the front, which is easily accessible to the hands of the wearer. A further object is to provide a garment having pocket space of variable capacity. A further object is to provide a garment of this type which is simple in construction and easy to make and launder. Other and further objects and advantages of the invention will be pointed out in the following more detailed description and by reference to the accompanying drawings wherein

Fig. 1 is a front perspective view showing a child's garment embodying the invention as it appears when worn;

Fig. 2 is a fragmentary elevation, to larger scale, illustrating the upper part of the garment so arranged that the pocket space is of minimum capacity;

Fig. 3 is a diagrammatic section on the line 3—3 of Fig. 2;

Fig. 4 is a view similar to Fig. 2 but showing the bib dropped down to expose the fly front;

Fig. 5 is a diagrammatic section substantially on the line 5—5 of Fig. 2;

Fig. 6 is a front elevation of the garment turned inside out to show the pocket structure;

Fig. 7 is a view generally similar to Fig. 2 but showing the garment arranged to provide a pocket of larger capacity;

Fig. 8 is a diagrammatic section on the line 8—8 of Fig. 7;

Fig. 9 is a diagrammatic plan view of one of the front pieces of the body of the garment showing it attached to the waistband;

Fig. 10 is a plan view of the rear ply of the bib member;

Fig. 11 is a plan view of one of the constituent halves of the front ply of the bib member; and

Fig. 12 is a view generally similar to Fig. 1 but showing a modification.

2

Referring to the drawings, the garment, as illustrated in Fig. 1, comprises the legs 1 and 2, the waistband 3, the bib 4 extending up above the waistband when in normal position, and the shoulder straps 5 and 6 by means of which the garment is supported.

Referring to Fig. 4, the legs 1 and 2 are shown as meeting at the crotch 7. The waistband 3 is provided with an opening at 8 to facilitate donning and doffing the garment. The ends of the waistband are provided with complementary fastener elements 9 and 10, for instance, the engaging parts of a snap fastener. Below the opening 8 in the waistband the body of the garment is provided with overlapping portions to form the fly 13.

The front of the garment proper comprises two pieces 11 and 12 (Figs. 4 and 9) which are substantially alike in contour except that one is reversed as respects the other. Referring to Fig. 9, the part 12 has the substantially straight horizontal upper edge 14 which is united by a seam to the waistband 3. The part 12 also has the substantially straight rear edge 15 which is united by a seam to the back of the garment and the substantially straight forward edge 16 which overlaps the corresponding edge of the part 11 to provide the fly. The lower edge of the part 12 is downwardly curved, as indicated at 17, this edge beginning at the point 18 at the lower end of the fly and extending to the point 19 where the edge 17 joins the edge 15.

Each leg of the garment comprises a front member 20 (Fig. 11), the lower part L of which forms the front of the leg proper and has an integral upward extension X which terminates at the substantially straight horizontal edge 21. From this edge an edge 22 extends downwardly substantially vertically and then merges with a curve which extends outwardly to a point 23 where it intersects a substantially straight edge 24 which is connected by the out-seam of the leg to the rear member of the corresponding leg. The edge 24 intersects the bottom edge 25 of the front leg member. The opposite end of this lower edge 25 intersects an edge 26 which is united by the leg in-seam to the rear member of the leg. The upward extension X of the front member of the leg is provided with an edge 27 extending from the top edge 21 downwardly and intersecting the edge 26 at the point 28 which is located approximately at the crotch 7 in the completed garment. The edges 27 of the two pieces 20 are united by a seam S (Fig. 1), the upward exten-

sion **X** of the two front leg members collectively forming the front ply of the bib.

The rear ply of the bib, as shown in Fig. 10, consists of a single piece **29** of the selected material, this piece having a substantially straight upper edge **30** of a length approximately twice the length of the edge **21** of the part **20**. This piece **29** is of substantially inverted Y-shape, comprising the upright or stem portion **31** and the downwardly divergent legs **34** and **35**. These legs have substantially vertical lateral edges **36** and **37**, upper edges **32** and **33**, and downwardly curved lower edges **38** and **39**, respectively, which intersect at the point **40** which, in the completed garment, is located at the lower end of the fly, the edges **36** and **37** intersecting the edges **38** and **39** at the points **41** and **42**, respectively. The curvature of the edges **38** and **39** is substantially like that of the edges **17** of the parts **11** and **12**. The length of the edges **36** and **37** is substantially less than the lengths of the outer edges **15** of the front members **11** and **12** of the garment.

In the assembled garment, the edges **21** of the parts **20** are aligned and seamed to the upper edge **30** of the part **29**; the edges **27** of the parts **20** are seamed together as above described, and the edges **22** of the parts **20** are seamed to the edges **32** and **33**, respectively, of the part **29**, the corners **23** registering with the corners **41^a** and **42^a**, respectively, of the part **29**. The edges **36** and **37** of the part **29** are seamed to the outer edges **15** of the parts **11** and **12**, preferably by the same seam which unites the edges **15** to the rear part of the garment.

As thus assembled, the bib is of two-ply construction, as diagrammatically illustrated in Figs. 3 and 5, comprising the front ply consisting of the united parts **20** and the rear ply consisting of the single piece **29**, the latter being united to the front of the garment proper only along the edges **36** and **37** and by the seams **C** (Fig. 6) which unite the edges **17** of the front members **11** and **12** to the curved lower edges **38** and **39** of the inner ply of the bib. Since the seams uniting the edges **36** and **37** to the edges **15** are less in length than the edges **15**, and since the curved edges **32** and **33** of the part **29** are not caught into this seam, the margin of the two-ply bib above the points **41^a** and **42^a** are free from the front members of the garment proper, thus providing entrances at each side of the garment into the front pocket spaces **P** (Fig. 5) which are defined by the rear ply of the bib and the corresponding front member of the garment proper. These pockets are thus conveniently accessible to the hands of the wearer of the garment and provide ample space for storage and are provided without requiring the attachment of inside pouches with its attendant difficulties and cost, or the attachment of patch pockets upon the outside of the garment which are unsightly and subject to ripping.

The rear members of the garment are indicated at **43** and **44** (Fig. 6), respectively, these members extending from the waistband down to the bottoms of the legs. These parts may be constructed in accordance with conventional practice and need not be illustrated in detail.

In each side of the opening **8** in the waistband there is arranged one element **45** of a separable fastener device, and each lateral margin of the bib is provided with complementary fastener elements **46**, preferably a plurality of such elements spaced apart. The fastener elements employed may be snap fasteners of conventional type, or buttons and buttonholes, or any other suitable connection.

The straps **5** and **6** are permanently secured at their rear ends to the waistband of the garment, and at their front ends are each provided with one element of a separable fastener designed to have operative engagement with one of the fastener elements **46** carried by the bib. Preferably the straps **5** and **6** are provided with adjustable members, for example slide buckles or the like, which carry these fastener elements so that the effective lengths of the straps may be adjusted. However, if desired, the fastener element carried by the strap may be fixed to the strap and the strap may be made adjustable in any other desired way.

As illustrated in Figs. 7 and 8, it is possible by the arrangement described to vary the effective size of the pocket **P**. Thus, for example, if the middle one of the three fastener elements **46** illustrated be secured to the corresponding fastener element **43** on the waistband, the bib is caused to bulge forwardly, thus providing an enlarged pocket space. In this instance the strap is secured to the upper fastener element **46**. However, if a pocket of minimum dimensions be desired, the lowermost fastener element **46** is secured to the waistband and the strap may then be attached either to the upper fastener element **46** or to the middle one.

A slight modification is illustrated in Fig. 12 wherein the straps **5** and **6** are shown as provided with fastener elements **48** so located as to be in the proper position to engage, for example, the top fastener element **46** of the bib. In this instance the lower forward ends of the straps **5** and **6** are secured to the waistband, for example permanently or detachably if desired. With this arrangement the wearer of the garment may detach the bib so as to expose the fly opening without detaching the straps from the waistband.

The garment thus devised provides a wide range of adjustment, it provides a normally concealed fly opening and a bib, and gives ready and full access to the fly opening. At the same time it furnishes the wearer with an easily accessible pocket space of large capacity without requiring the application of pouch or patch pockets.

While certain desirable embodiments of the invention have been illustrated by way of example, it is to be understood that the invention is broadly inclusive of any and all modifications falling within the scope of the appended claims.

I claim:

1. A bifurcated overall garment having a waistband which opens at the front, a fly front and a bib, the bib normally covering the fly but being capable of dropping to expose the fly, the bib being of a length to extend to a substantial distance above the waistband, one element of a separable fastener arranged at each side of the opening at the front of the waistband, and a plurality of spaced complementary fastener elements at each side of the bib for selective engagement with the fastener element on the waistband, whereby the upper edge of the bib may be adjusted to different heights.

2. A bifurcated body garment comprising a waistband, the body of the garment comprising two front members each having a substantially straight upper edge secured to the waistband, a substantially straight rear edge for attachment to a rear part of the garment, a substantially straight front edge and a curved lower edge, and a bib comprising a front ply and a rear ply, the front ply extending down below the crotch and forming the fronts of the two legs, the rear ply

being of substantially inverted Y-shape, the arms of the Y having curved lower edges, and means uniting the curved lower edges to the front members of the garment body to the curved lower edges of the Y-shaped rear ply of the bib, thereby providing pockets between the front members and the rear ply of the bib, and means uniting the outer edges of the Y-shaped rear ply of the bib to the rear edges of the front members of the garment body.
